UNITED STATES PATENT OFFICE.

NORMAN ROBERT NEWSHOLME, OF KEIGHLEY, ENGLAND.

DOFFING MECHANISM FOR SPINNING FRAMES.

1,353,414.

Specification of Letters Patent. Patented Sept. 21, 1920.

Application filed October 30, 1918. Serial No. 260,385.

To all whom it may concern:

Be it known that I, NORMAN ROBERT NEWSHOLME, subject of the King of Great Britain and Ireland, residing at Southlands, 5 Keighley, in the county of York, England, have invented new and useful Improvements in and Relating to Doffing Mechanism for Spinning-Frames, of which the following is a specification.

10 This invention relates to improvements in doffing mechanism for spinning frames and refers more particularly to that class of doffing mechanism in which is employed duplicate spindle rails and spindles therefor—an example of which is known in the 15 specification of Letters Patent No. 24392 granted to me under date Oct. 28th 1913. In this case the mechanism comprised duplicate rails and spindles therefor adapted to 20 carry caps or fliers combined with rack members and slides for transferring one rail from a spinning to a "setting" position and the other from the setting position to a spinning one the movement being first horizontal 25 and then vertical. The present invention is an improvement in or modification of the before mentioned invention and deals with duplicate spindle rails and lifter plates which are each transferable from the setting 30 to the spinning position and vice versa. One rail or like balancing the other, and as one rail is moved out of the spinning position, the other moves in. The rails or like can 35 hardly be said to be detachable as they will be generally mounted on supports or in slides and will have a movement up and down only in such supports or in such slides. The arrangement and construction is one which lends itself readily to ordinary cap, fly, or 40 ring spinning frames.

In describing my invention in detail reference is made to the accompanying sheet of drawings similar letters indicating similar parts in which:—

45 Figure 1 represents an elevation of a portion of a frame with my improvement added as applied to a cap spinning frame.

Fig. 2 represents a view of the guide rods and balancing means for the rails.

50 Fig. 3 represents a section with a guard plate in position.

Fig. 4 represents details of the guard cutter device hereinafter referred to.

55 Fig. 5 represents an elevation of a portion of a frame with my improvement added thereto as applied to a fly spinning frame.

Fig. 6 represents an end view of the guide rods and slides shown in Fig. 5.

Fig. 7 represents a side view of the clutch mechanism and connections.

Fig. 8 represents in plan the lifter rails or plates with a cut away portion hereinafter described and

Fig. 9 represents a section through a cutter bar and means for carrying same.

Fig. 10 is an enlarged detail side view showing the apparatus for stopping the rotation of the spindle-elevating shaft.

Figs. 11 and 12 are fragmentary side elevations, on an enlarged scale, of the means 70 for tilting the rear spindle rail, Fig. 12 being a view at right angles to Fig. 11.

Fig. 13 is a fragmentary side elevation, on an enlarged scale, illustrating one manner of forming a hinge in the depending rods for 75 positioning the lifter rails.

In carrying my invention into effect, I will make no reference to holding devices employed in doffing mechanism in connection with fliers or caps, nor with arrangements for releasing the tapes or driving bands from the whirls of revolving tubes or spindles but simply describe the duplicate balanced rails which are not interchangeable one with another, but which move from the 85 spinning to setting position each in its own course, I will describe that form which I anticipate will give the best results in the simplest manner, although I wish it to be understood that I may arrange the balanced 90 rails in other ways than that hereinafter set forth.

Each of the spindle rails S S^x say for a "cap" doffing machine carries its own set of spindles S' S² and its own lifter plate L L^x, 95 the whirls and tubes being of the ordinary pattern and driven in the ordinary manner, but the driving tapes may be freed from the whirls during doffing in any known manner. Each rail is mounted on its own guide rods 100 or slides G' G, there being a suitable number, arranged by preference to form as it were two sides of a triangle, a supporting or connecting member at the base forming the third side, and during spinning one 105 spindle rail S say the rear one will form the apex of such triangle. The lifter plates will be engaged by suitable lifting rods L⁴ in any convenient manner and will also carry depending rods L' L² which serve to position 110 the lifter plate and consequently the bobbins and tubes or like during setting.

Suitable brackets G^2 will embrace the guide rods and carry the spindle rails S and S^* , the connection of each rail to its own guide rods being similar.

5 The shaft C^2 is rotated by means of a suitable hand wheel C^3 , after the spinning is finished thereby to move the full spindle rail, as for instance S , out of spinning position, the rail sliding downward on its guides G , while the other rail is pulled by the cord or chain C up into spinning position. The shaft C^2 is held against rotation when a rail is in spinning position by means of a pulley or roller C^6 (Figs. 1 and 10) secured on the shaft and provided in its periphery with a pair of diametrically oppositely disposed recesses C^8 , a handle C^5 being pivoted above said drum C^6 and having a depending lug C^4 adapted to contact with one of the walls 10 of said recesses and so prevent rotation of the shaft. For example the full rail may move down the rear guides and the empty one up the front guides. The lifter depending rods L' L^2 will come in contact with the ground see Fig. 1, and hold the lifter rail and bobbins while the spindle rail descends. Means will be provided to tilt the rear spindle rail in order to facilitate setting, such as by narrowing the guide rod G' at or toward its base G^3 and by providing a slot G^4 in the rail supporting bracket G^2 which will allow such narrowed portions to pass and a catch, arm or projection H or like may be provided on the frame and adapted 15 to contact with the rail S^* at the proper time to tilt the same, as shown in Fig. 12, to effect such tilting. The depending rods L^2 for positioning the lifter rail and bobbins may be provided with knuckles or 20 hinges L^3 preferably as shown in Fig. 13 to allow same to bend in order to clear or pass mechanism which would otherwise tend to obstruct the movement of the rails.

25 A suitable guard plate A hinged to the front of the frame as for example from the guide rod G' as at A' Fig. 3 may be employed to guard the slightly projecting spindles and bobbins to the front of the frame, and this guard plate may have an edge adapted to engage the "ends" of yarn 30 to facilitate severing operations, or be in the form of sliding cutter A^2 well known. This arrangement may not be essential for every form of spinning frame, but it has advantages which will be obvious.

35 Suitable means for severing the yarn will be provided such for example as ordinary notched flanges on the tubes or revolving spindles when such are used, or the edge of 40 the guard plate hereinbefore mentioned which may itself be the cutter, as shown in Fig. 4.

45 This guard plate A may be turned out of position against the action of a spring A^3

50 arranged somewhat as shown in Figs. 1 65 and 3.

55 The first operation is to lower the lifter rails to their lowest position, and then disengage them from the rods. One method of disengagement is to carry from the upper end of the lifter rods a bracket or rod 70 which normally engages the lifter rail. This bracket or rod is slidably mounted on the lifter rod, and is pushed or pulled out of engagement with the lifter plate by any 75 suitable means for example.

60 It will be seen that the parts are simple and the operation practically one movement, that is, one rail, balanced by the other moves from spinning to setting position and the 80 other from setting to spinning position, each rail moving up and down on its own supports or in its own guides at a slight angle; the rear one toward the frame and the front one slightly away from it on the downward 85 movement. The rails are interchangeable only as to spinning position.

65 The actual operation of moving the rails is carried out by one shaft or handle and when fliers and caps do not require to be 90 held as is the case when the spindles are dead and fliers are held independent thereof, a simple doffing movement is evolved by using the guide rails or slides, and mounting thereon the lifter plates which carry the 95 spindles. These plates are balanced and are operated from an essential spinning motion namely the lifter motion, and the complete doffing motion is carried out by turning the operating shaft one revolution or part of a 100 revolution in one direction and then returning the shaft and its handle to the original position, there being combined with the mechanism a suitable yarn severing device. This mechanism is hereinafter described. 105 It being understood in this case spindle rails *per se* are not required, the lifter rails and their spindles (each set) being moved in their respective paths, on their slides or guides and an end-wise movement being given to 110 the rails to clear the lifting rods.

70 In the form of mechanism for flier frames having their spindles carried on the lifter rails and the fliers independent of the spindles and driven from above, I have where 115 possible in the drawings used the same letters of reference as those used in the first mentioned form to designate similar parts and S S^* represents the spindle or lifter rails.

75 The lower rail B carries hollow supporting members B' within which the lifter rods L^4 operate, such rods being operated from a shaft C^2 having a chain connection C^8 to the lifter motion, that is to say this shaft C^2 120 is rotated by the lifter mechanism during spinning and the lifter rods are operated from the shaft C^2 there being a chain con-

nection C^{14} to the lifter rods L^4 substantially as shown in Fig. 7. From the shaft C^2 by suitable driving means such as chains or like C^6 Fig. 7 is driven a clutch member O having engaging faces O^4 O^5 to engage 5 slideable but nonrevoluble collars O^6 O^7 on the lower shaft O' suitably carried as by bearings O^2 upon the lower rail B . At each 10 end of this shaft O' are chain wheels or pulleys O^3 Fig. 6 having connections to the slides, holders, or carriers G^2 which operate on the guide rods or like G G' . There may be a suitable number of guide rods and carriers with connections to the shaft O' one 15 only being shown in Fig. 6. Each carrier G^2 carries a support G^5 on which its respective rail S or S^* will rest when lowered thereon by lowering the lifter rails through the lifter motion, each lifter rail will carry 20 an extension or arm S^3 adapted to embrace the guide or like.

The lifter rods L^4 engage the rails S and S^* by means of a side bracket L^5 Fig. 7, the nose L^6 of the said rod entering an aperture S^4 in the rails tapered outward, toward 25 the rear edge on the front rail, and toward the front edge in the back rail as shown in Fig. 8, to enable the rails to be interchanged as to position with reference to 30 the common lifting rods. As one rail descends or rises it is given an end-wise movement by forming on the guides cam like projections G^6 Figs. 5 and 6. As the rails move down the guides, the end brackets S^3 35 will follow the path of the guide and so move outward and on encountering the projections G^6 also move endwise and so clear the lifting rods by permitting the side bracket L^5 to be positioned in the aperture, 40 the nose L^6 following the taper side of the aperture. The upward motion of the other rail places it in position on the lifter rods, it being understood that the guide rods are 45 farther apart toward their base than at the top.

During the downward motion of the rails it is necessary to actuate the shaft O' as the carriers G^2 do not of necessity move up or down the full extent of the travel of the 50 spindle rails. The lowering of the lifter rods lowers one rail on to its support G^5 and then the lifter rod has no further action until it is required to raise the other rail, therefore each rail carries a downwardly 55 projecting finger such as F Figs. 5 and 7 that on the front rail being adapted in falling to engage and operate a clutch lever F^2 which puts the shaft O' into gear with the clutch member O in one direction and 60 so operates the slides in the desired direction. The rear rail finger F as it descends operates the shaft O in the other direction by engaging through clutch lever F^2 the collar O^7 and member O , change of direction 65 being given through a train of wheels O^8

and chain or like wheels O^9 , Figs. 5 and 7. To facilitate setting, the rear rail may be tilted by forming fingers T on same to engage, as it nears the lowest position, fingers or projections suitably mounted on the 70 machine frame or on the floor, illustration of such projections being omitted for the sake of clearness.

Some device is necessary to enable the operating shaft C^2 to be actuated without operating on the lifter mechanism, therefore the lifter chain or like wheel C^7 is mounted loosely on its shaft and provided with a suitable clutch mechanism attached to the shaft. When the clutch mechanism is disconnected 80 the shaft C^2 may be operated without turning the wheel C^7 , a simple form is shown in Fig. 5 wherein on the handle C^8 is mounted a lever C^{15} adapted through a finger C^9 to pull against the action of a spring C^{10} , a 85 sliding collar C^{11} having thereon a stop or like pin (not shown) normally in engagement with an indent, recess, or like formed in the hub portion C^{13} of wheel C^7 .

To operate the mechanism and doff, the 90 before mentioned clutch is released, the handle turned in one direction, the rail to be lowered is moved down by the lifter rods and its own weight until the carriers are reached, a further partial turn of the handle 95 (the lower shaft now operating) causes one carrier to be lowered and the other raised, the endwise movement of the rails taking place about this time. The operating handle is then returned to its original position, the 100 lifter rods engaging and bringing the empty rail up into spinning position. The yarn is severed and spinning is resumed, the whole operation being exceedingly quick and simple.

Some severing device is necessary and I have devised means whereby one cutter may serve both rails. Each rail is provided with a series of U shaped holders P . On the front rail they project to the back, and on 110 the back rail to the front.

In one set of holders I mount on suitable clip like feet P^1 Fig. 9 a cutter bar P^2 of the notched or sliding variety preferably one consisting of two stationary edges as shown 115 in section in Fig. 9 with one notched sliding bar P^3 acting in between. The holders of one rail are not opposite those of the other. As one rail falls the holders of the falling rail leave the cutter and those of the 120 ascending one embrace same and thus one cutter serves both rails.

To insure the cutter assuming a correct position I mount the holders P on their rails so as to give them a spring or yielding action 125 downward and as the rails are raised the ends of the cutter bars will come into contact with suitable stops such as P^4 Fig. 5 and depress the cutters and their holders.

Having explained my construction what I 130

claim as my invention and desire to secure by Letters Patent is:—

1. Doffing mechanism for spinning frames comprising, in combination duplicate spindle carrying rails, with fixed guides for each rail, said guides being inclined one to the other to allow the rising and falling rails to pass.
2. Doffing mechanism for spinning frames comprising, in combination duplicate spindle carrying rails adapted to move up and down each in its own path and a guard plate to protect the front bobbins and also act as a severing device for the yarn.
3. Doffing mechanism for spinning frames comprising, in combination duplicate spindle carrying rails each operating in its own path into and out of spinning position, lifter rods therefor and means connected with the said path to give an endwise movement to the rails thereby to clear said lifter rods.
4. Doffing mechanism for spinning frames comprising, in combination duplicate spindle carrying rails each operating in its own path into and out of spinning position, lifter rods therefor and means operative during such movement to disengage and engage the lifter rods from the rails.
5. Doffing mechanism for spinning frames comprising duplicate spindle carrying rails, each operating in its own separate path into and out of spinning position, lifter rods therefor, a rotatable shaft for operating said lifter rods, and means operative on the descent of either of said rails for rotating said shaft.

In testimony whereof I have signed my name to this specification.

NORMAN ROBERT NEWSHOLME.
